UNITED STATES PATENT OFFICE.

ANDRÉ BLONDEL, OF PARIS, FRANCE.

ELECTRIC-ARC LAMP.

SPECIFICATION forming part of Letters Patent No. 764,105, dated July 5, 1904.

Application filed December 22, 1903. Serial No. 186,163. (No model.)

To all whom it may concern:

Be it known that I, ANDRÉ BLONDEL, a citizen of the Republic of France, residing at Paris, in the Republic of France, have invented a new and useful Improvement in Arc-Lamps, which improvement is fully set forth in the following specification.

The specification of the United States Patent No. 739,977, dated September 29, 1903, describes a combination of arc-lamp in which a largely mineralized scoria-producing carbon may be used by placing it beneath another less mineralized carbon, the latter surrounded by a dome or reflector provided with a refractory base which prevents the vapors passing away, thus allowing the fumes to be maintained in the arc. These are brought to incandescence and prevented from condensing upon the upper point, which parts with its heat to a very limited extent. The specification also claims the novel application of the dome to all mineralized arcs in view of the special results obtained.

This invention has for its object an improvement by which the amount of mineral substances in the upper carbon (whatever may be its polarity) may be increased, if desired. A special disadvantage presents itself in this case consequent on the formation of scoria around the point of the upper carbon so soon as its mineralization is greater than seven to eight per cent. The scoria forms, as shown in Fig. 1, a swell around the point of the carbon, where it collects instead of falling in drops. This swell thereupon prevents the upper carbon from moving freely upward through the hole in the reflector when striking the arc and when drawing it out by the top when the carbons are changed. Moreover, the scoria may ultimately attack and fuse the refractory material forming the reflector, (which may be a dome, crucible, or disk,) which surrounds the carbon near to its point. Lastly, it falls in drops upon the point of the lower carbon.

The improvement forming the object of the present invention consists in surrounding the upper carbon with a protecting-envelop *a* of carbon, which not only enormously reduces the formation and fall of scoria, but also forms (in order to allow the carbon to be easily with-

drawn) a space between the scoria-forming portion of the carbon and the walls of the hole in the reflector. The said hole may, moreover, be advantageously cut away for a certain distance toward the bottom, forming a conical, 55 spherical, cylindrical, or other enlargement, as shown in Figs. 3, 5, and 6, in order to more surely prevent scoria touching the walls. Figs. 2, 3, 4, 5, and 6 show examples of this envelop in several different forms of reflector. 60 The carbon envelop is consumed little by little and should consequently be fed forward bit by bit. This forward movement may take place in one or other of the following ways:

First. As shown in Fig. 6, the top of the envelop (which is shorter than the upper carbon) is fixed in an independent annular carbon-carrier, supported by a rod, chain, or cord analogous to that which supports the carbon-carrier of the central carbon and receives through 70 the lamp mechanism a similar but smaller movement than that of the carbon. The said movement is empirically regulated in such a manner that the advance is proportional to the consumption. It is not necessary to enter 75 here into the details of the mechanism, which is capable of numerous forms within the reach of any mechanic.

Second. As shown in Figs. 2, 3, 4, and 5, the envelop of the carbon, which it surrounds, 80 is so fixed that the envelop advances with the carbon without separating from it. The thickness of said envelop is so chosen that it is consumed as fast as the inner carbon and leaves the carbon always flush with it or projecting a little out from the said envelop. The envelop may even be manufactured together with the carbon and have given to it conducting properties advantageous to the 85 passage of the current and the decrease of 90 consumption, according to the arrangements indicated in Blondel's patent, No. 714,277, of November 25, 1902. These carbons then have the advantages indicated in this patent and also the additional advantages of the combination set out above, which render the employment of the reflector more practical. The envelop may also be made fairly thick when the reflector is quite open, as when disk-shaped, as shown in Fig. 4, or when it is de- 100

sired that the end of the upper carbon should project still more below the reflector, as shown in Fig. 8, for in these two cases the consumption of the envelop is increased, for the carbon is completely exposed to the free air.

Third. A last and slightly-different solution is for the envelop to form the base of the reflector surrounding the carbon, as shown in Fig. 7—that is to say, this portion of the reflector may be made of pure carbon, which is little combustible if of a graphite-like nature or mixed with small quantities of mineral substances—for example, magnesia or non-inflammable substances which form white cinders at the lower surface. Such a piece of carbon consumes slowly and may be easily renewed when changing the carbons. As it is very refractory and not attacked by scoria, it may be placed around the point of the carbon quite near to the arc.

These different arrangements of carbon envelops placed between the upper carbon and the reflector find application in several cases in which a mineralized arc is used, viz:

25 First. In a continuous-current arc, the positive being above and the negative below, the arc being formed between any carbon, whether ordinary or mineralized, whether homogeneous or provided with a core and with or 30 without an envelop. In this combination the positive is kept hotter than when the arc is inverted; but there may be an excess of scoria if the mineralized portion of the positive carbon be too highly mineralized. A mineralization of twenty-five per cent., for example, 35 would be sufficient.

Second. In a continuous-current arc having the positive placed underneath when it is wished to more highly mineralize the negative, the positive being, if desired, also mineralized.

Third. In an alternating-current arc having both carbons mineralized.

In all these applications the reflecting dome, 45 crucible, or disk still possesses the useful properties already mentioned.

Fourth. Lastly, in continuous-current lamps of any type having any number of carbons mineralized (or in which one at least is mineralized) placed side by side with points downward, Fig. 8.

In this case, again, a notable improvement in these lamps is effected, for not only does the covering of carbon reduce the fall of scoria 55 and protect the holes in the reflector, as above

stated, but it also permits the arc to be formed with safety by moving the two carbons together. In effect, even if drops *b* are formed in the lower portions of the envelop *a* remain clean, and excellent contact may be formed 60 between them when the carbons are lowered until they touch each other.

What I claim is—

1. In an arc-lamp, the combination, with a reflector having an opening, of a mineralized 65 movable electrode projecting through said opening, and a protective envelop extending into said opening and surrounding the mineralized electrode.

2. In an arc-lamp, the combination, with a 70 reflector having an opening, of a mineralized movable electrode projecting through said opening, and a protective carbon-envelop extending into said opening and surrounding the mineralized electrode.

75 3. In an arc-lamp, the combination, with a carbon reflector having an opening, of a mineralized movable electrode projecting through said opening, and a protective carbon-envelop extending into said opening and surrounding the mineralized electrode.

4. In an arc-lamp, the combination, with a reflector having an opening, of a mineralized movable electrode projecting through said opening, and a protective envelop extending 80 into said opening and surrounding the mineralized electrode, said envelop being movable with relation to said electrode.

5. In an arc-lamp, the combination, with a reflector having an electrode-opening, of a 90 scoria-producing electrode movable through said opening, and a protective envelop surrounding said electrode and extending into said opening in the reflector.

6. In an arc-lamp, the combination, with a 95 reflector having an electrode-opening, said reflector being cut away adjacent said opening, substantially as described, of a scoria-producing electrode movable through said opening, and a protective envelop surrounding said 100 electrode and extending through said opening in the reflector.

In testimony whereof I have signed this specification in the presence of two subscribing witnesses.

ANDRÉ BLONDEL.
